MEANS FOR THE EXPANSION OF
CIRCULAR TABLES

Adlai H. Eliason, Mooresville, N. C.

Application July 12, 1946, Serial No. 683,269

2 Claims. (Cl. 311—66)

1

This invention relates to mechanical means for the progressive expansion of a circular area, and more particularly to mechanical means having a wide range of applicability to articles incorporating circular areas adapted for progressive expansion while substantially retaining the circular character thereof.

The invention has for its chief object the provision of a mechanical structure having a surface area of circular configuration and of means cooperable therewith for accomplishing an increase of the surface area thereof without substantially changing the circular configuration thereof.

A further object of the invention is to provide a mechanical structure of the kind referred to having a surface area of circular configuration, divided into separable parts, and embodying supporting structure therefor, whereby said parts and supporting structure are capable of extension to cooperate with removable sections to form a substantially circular surface of increased area.

Other objects and advantages of the invention will become evident from the following description of the same, constituting a specification thereof, when considered in connection with the annexed drawings.

The invention comprises, briefly stated, a mechanical structure, such, for example, as an extension table, having a top surface of circular configuration, divided into a rectangular center portion and segmental side portions with outwardly curved sides, and extensible supporting structure for said side portions whereby the same can be extended for cooperation with specially shaped removable leaf parts for increasing the area of the top surface while substantially retaining the circular configuration thereof.

In the drawings:

Figure 1 is a plan view of the invention, partly broken away to reveal the details of supporting structure of the extensible side portions, and the manner in which the removable leaf portions cooperate therewith.

Figure 2 is a side view, partly in section, taken along the line 2—2 of Figure 1, and

Figure 3 is a perspective view of one of the removable leaves.

Referring to the drawings in greater detail, 1 indicates a rectangular member forming the center section of the top of a mechanical structure, such as an extension table or other structure having an extensible surface. 2, 3, 4 and 5 represent identical segmental side sections forming with the center section 1 a top area of circular

2

configuration. Each of the segmental sections 2, 3, 4 and 5 has a straight side 6 adapted to fit against one of the sides of the center section 1, and a curved side 8 of such shape that together the sections 1, 2, 3, 4 and 5 form a perfect circular area.

The supporting structure for the sections just described may comprise an apron 10 of circular shape lying beneath the sections, the cross stretcher 11 of suitable shape fitting within the apron 10 in spaced relation beneath the sections, and braces 12 and 14 two of which are provided for each of the extensible sections 2, 3, 4, and 5.

15 The braces 12 and 14 are pivotally secured at their outer ends to the under sides of the segmental sections by vertical pivot means 16, such as wood screws. The braces 12 and 14 extend through notches 18 and 19 and are slidably inserted between the section 1 and the cross stretcher 11. Notches 18 and 19 are of such a depth that the bottom surfaces of the braces 12 and 14 bear upon the upper surface of stretcher 11 and the bottoms of the notches and are supported thereby. Vertical pins 20 project above and below the inner ends of the braces 12 and 14 20 for cooperative engagement in curved grooves 22 and 23 provided in opposed surfaces of the section 1 and cross stretcher 11 for a purpose inserted between the section 1 and the cross stretcher 11. Notches 18 and 19 are of such a depth that the bottom surfaces of the braces 12 and 14 bear upon the upper surface of stretcher 11 and the bottoms of the notches and are supported thereby. Vertical pins 20 project above and below the inner ends of the braces 12 and 14 for cooperative engagement in curved grooves 22 and 23 provided in opposed surfaces of the section 1 and cross stretcher 11 for a purpose later to be made apparent. The pins 20 may carry rollers or other anti-friction means, not shown, for facilitating movement in the grooves 22 and 23.

25 It will be seen from an inspection of Figure 1, 35 that the segmental sections 2, 3, 4 and 5 may be extended by pulling the same out away from the center section 1, thereby extending the braces 12 and 14. As the sections 2, 3, 4 and 5 are moved toward or away from the respective sides of the center section 1, the inner ends of the braces 12 and 14 are guided away from or toward each other by the action of the pins 20 in grooves 22 and 23. This arrangement of the inner ends of the braces 12 and 14 prevents any interference of 40 the same with the ends of other braces when the sections 2, 3, 4 and 5 are in their innermost positions. The notches 18 and 19 are of a width to permit the movement of the braces 12 and 14 as just described.

45 Figure 3 illustrates a removable leaf 25 adapted for cooperation with the above described expandable structure for increasing the area of the same. The leaf 25 may be of any desired width which will fit between the side 6 of one of the segmental sections 2, 3, 4 and 5 and the respec-

tive side of the center section 1, when the segmental sections are extended. Such leaves may be provided in different widths in order to secure a greater or lesser increase in the available surface area. Each leaf 25 is preferably formed with tapered end portions 26 and 27 each formed by sides 28 and 29. The sides 30 and 31 of the leaf 25 are of the same length as the sides 6 of segmental sections 2, 3, 4 and 5 and the corresponding sides of the center section 1.

As best seen in broken lines at the left of Figure 1, when the leaf 25 is inserted in position between one of the segmental sections 2, 3, 4 and 5 and the respective side of the center section 1, the portions 29 of the ends 26 and 27 form parts of the circumference of a substantially circular surface of greater area than that formed by the sections 2, 3, 4 and 5 and the center section 1. The portions 28 of the leaf 25 abut identical portions on the ends of adjacent leaves, thus completing the circular configuration of the increased area.

Legs 32 may be provided attached at suitable points on the circumference of the apron 10 in case the structure takes the form of an extension table.

The operation of the mechanism will be apparent from the above description of the same. To increase the circular area, the segmental sections 2, 3, 4 and 5 are pulled out, and leaves 25 inserted between the sides 6 and the opposed sides of the center section 1. The leaves 25 will then be supported upon the upper surfaces of the braces 12 and 14 and the upper edge of the skirt 10 and will form with those sections a continuous substantially circular surface of increased area. The braces 12 and 14 in their extended positions are parallel to each other, as seen in Figure 1, and in retracted position beneath the central portion 1, the braces are in substantially radial relation to the circular area.

It will thus be seen that the invention as described above provides a simple and ruggedly constructed device, characterized by a surface of circular configuration which is capable of being progressively extended in any desired degree while substantially retaining its circular character.

It will of course be understood that the above described embodiment of the invention is intended for purposes of example only, that the principles of the same are capable of incorporation in a wide variety of structures useful in many different ways, and that numerous changes may be effected in the structure and arrangement of the parts of the same, without departing from the spirit of the invention or the scope of the appended claims.

Having thus clearly shown and described the invention, what is claimed and desired to secure by Letters Patent is:

1. In an expandible circular table top including an equilateral polygonal center section bounded

by like marginal sections each comprising a segment of a circle, the improvement comprising a pair of spaced braces mounting said marginal sections for sliding movement radially outwardly of said center section, a leaf insertable between each marginal section and said center section, said leaves being supported on said braces in flush relation to said center and marginal sections, each leaf comprising parallel sides of like length

10 and substantially identical pointed ends, each of said braces including outer and inner ends, means providing pivots connecting said outer ends to said marginal sections for pivotal movement in a horizontal plane, said center section being formed with a pair of radially inwardly converging slideways for each pair of braces, and said inner ends of each pair of braces including means slidably guided in a pair of slideways.

2. In an expandible circular table top including an equilateral polygonal center section bounded by like marginal sections each comprising a segment of a circle, the improvement comprising a pair of spaced braces mounting said marginal sections for sliding movement radially outwardly of said center section, a leaf insertable between each marginal section and said center section, said leaves being supported on said braces in flush relation to said center and marginal sections, each leaf comprising parallel sides of like length and substantially identical pointed ends, a stretcher co-extensive with said center section, means mounting said stretcher in downwardly spaced relation to said center section, each of said braces including inner and outer ends, means providing pivots connecting said outer ends to said marginal sections for pivotal movement in a horizontal plane, said center section and stretcher each being formed with a like pair of radially inwardly converging grooves for each pair of braces, and the inner end of each brace including upwardly and downwardly directed means slidably guided in grooves of said center section and stretcher.
